US00D526638S

(12) **United States Design Patent** (10) **Patent No.:** **US D526,638 S**
Farkas (45) **Date of Patent:** **** Aug. 15, 2006**

(54) **CAR SHAPED CELL PHONE AND FLASHLIGHT**

(76) Inventor: **Matthew S. Farkas**, 315 Conover Pl., Red Bank, NJ (US) 07701

(**) Term: **14 Years**

(21) Appl. No.: **29/212,535**

(22) Filed: **Sep. 3, 2004**

(51) **LOC (8) Cl. 14-03**

(52) **U.S. Cl. D14/143; D21/548; D26/38**

(58) **Field of Classification Search** D14/137, D14/138, 143, 144, 147, 148, 149, 150, 218, D14/250; D13/168; 379/428.01, 428.02, 379/433.04, 433.07, 433.11, 434, 451, 452; D26/32, 37, 38, 47, 51, 52, 57, 94, 97
